UNITED STATES PATENT OFFICE.

CHARLES O. MASON, OF ATTLEBORO FALLS, MASSACHUSETTS.

BOX-FASTENER.

942,839.

Specification of Letters Patent. Patented Dec. 7, 1909.

Application filed July 19, 1909. Serial No. 508,443.

To all whom it may concern:

Be it known that I, C. O. MASON, a citizen of the United States, residing at Attleboro Falls, Massachusetts, have invented certain new and useful Improvements in Box-Fasteners, of which the following is a specification.

My invention relates to improvements in box fasteners, and comprises the novel construction hereinafter described and particularly defined in the appended claim.

The invention is illustrated in the accompanying drawings, in which—

Figure 1 is a plan view of a blank which constitutes my improved fastener; Fig. 2 is a sectional view of a box with the fastener applied; and Fig. 3 is a similar view showing how the auxiliary fastening device actuates in case the holding tongue should be accidentally bent up.

Referring by reference characters to this drawing, the numeral 1 designates a box of pasteboard or cardboard, such as designed for shipping small articles through the mails, and 2 the cover thereof.

3 designates the fastener which is designed to be applied to each end of the box, as shown in Fig. 2, and which has side wings 4 which are bent at right angles, and inserted through slits in the edge of the box and bent over to hold the fastener in place. The tongue 5 is designed to pass through a slit in the cover, as shown, and then be bent over the end of the cover on the outside, as shown in Fig. 2, to hold the cover in place. Centrally of the body of the fastener is provided an auxiliary tongue 6 formed by slit-

ting the metal of the fastener, and when the main tongue is in the position shown in Fig. 2, this auxiliary tongue lies flush with the body of the fastener, as shown, as it does also when the fastener is first applied to the box. Should, however, the main fastening or holding tongue be accidentally bent up during transit in the mails, rendering the cover liable to come off, the bending up of the main tongue will cause the auxiliary tongue to be bent or inclined outwardly against the inside of the cover of the box, as shown in Fig. 3, and thereby act as a pawl or engaging device to prevent the accidental displacement of the cover. The inside of the cover may be notched or scored to assist in the holding action.

Having thus described my invention what I claim is:—

In combination with a box and its cover having a slit therein, a fastener secured to the box and having a foldable cover engaging tongue passing through the slit, said fastener having an integral auxiliary tongue for engaging the inside face of the cover, said auxiliary tongue having its base in proximity to the line of fold of the main tongue whereby it will be moved outward into engagement with the cover when the main tongue is straightened, substantially as described.

In testimony whereof, I affix my signature in presence of two witnesses.

CHARLES O. MASON.
